APPARATUS FOR CHANGING THE ION
SOURCE OF A CYCLOTRON

John J. Livingood, John V. Peters, and Royal A. Streeter, Cedar Rapids, Iowa, assignors to Collins Radio Company, Cedar Rapids, Iowa, a corporation of Iowa

Application April 27, 1950, Serial No. 158,512

16 Claims. (Cl. 250—27.5)

1

This invention relates in general to cyclotrons, and in particular to apparatus for automatically removing the cathode and anode of an ion gun from a cyclotron without the necessity of a person being present in the room.

With the development of the field of nuclear physics there has arisen the need for man-made machines which will induce radioactivity in normally inert materials. A study of the resultant radioactivity gives a hint to the structure of the activated atom. One of the machines built for inducing radioactivity is the cyclotron. When the cyclotron is operated, the region in its vicinity is subjected to very concentrated radiation. Even after the machine is turned off, a large amount of residual radiation exists. It is well known that the human body can be safely exposed to a particular intensity of radiation for just so long. In some of the large cyclotrons now in operation this time is three minutes per day, even when the machine is turned off. In other words, when the cyclotron is operating and is momentarily shut down for adjustment, the person making the adjustment should not remain in the cyclotron room more than a few minutes. The operation of the cyclotron is usually controlled from an adjoining room which is shielded by lead or other suitable material from the harmful radiation. One of the requirements for the operation of a cyclotron is that there must be an ion source, and the type of ion source used has a hot filament, generally of tungsten, over which a suitable gas moves and the electron emission of the high negative filament results in the formation of ions. These ions are the "bullets" of the cyclotron. At the extremely high temperatures which the tungsten filament must be operated, it is frequently necessary to replace the filament. Previously an operator has entered the room and hurriedly removed the filament and replaced it. The dee chamber of the cyclotron must be maintained at a very low pressure, and before the filament may be removed it must be pulled through a pressure lock which prevents the atmospheric pressure from spoiling the vacuum in the chamber. This takes time, and the operator is being needlessly exposed to harmful radiation.

It is an object of this invention, therefore, to provide apparatus for automatically removing the ion source of a cyclotron without the necessity of an operator being present in the cyclotron room.

Another object of this invention is to provide means for automatically withdrawing the cath-

2

ode of a cyclotron from the dee chamber without losing the vacuum in the cyclotron.

Yet another object of this invention is to provide means for automatically changing the cathode which has been removed from the cyclotron and re-positioning the new one in the dee chamber.

Still another object of this invention is to provide means for automatically removing and replacing the anode of a cyclotron.

A feature of this invention is found in the provision for a track which carries a first carriage to which the cathode is connected, and a second carriage to which the anode is connected. Means are provided for automatically moving the carriages longitudinally of the cyclotron through suitable pressure chambers. The replacement cathodes and anodes are mounted on a movable cart which can remove the old parts and replace them.

Further objects, features, and advantages of this invention will become apparent from the following description and claims when read in view of the drawings, in which:

25 Figure 1 is a top sectional view illustrating a cyclotron and an operator in an adjoining room manipulating controls for automatically removing the ion source;

30 Figure 2 is a side view of the ion source removing apparatus;

Figure 3 is a sectional view taken on line A—A of Figure 4, and illustrates the removal and replacement mechanism for the ion source;

35 Figure 4 is a rear view of the carriage for removing the ion source members;

Figure 5 is a detailed view of supporting means for holding the free end of the cathode and anode as they are withdrawn from the dee chamber.

40 Figure 6 is a detailed view of the anode door; and,

Figure 7 is an end view of the cathode carriage.

Figure 1 illustrates a cyclotron comprising the dees 10 and 11 which are surrounded by the dee chamber wall 12. An ion source 13 extends into the dee chamber formed by the wall 12 and terminates between the dees. It is to be understood, of course, that the head 14 extends up between the dees whereas the longitudinal portion of the ion source 13 is below the plane of the dees so that it does not interfere with the path of the accelerated particles. The ions emerge from the head 14 of the ion source and are actuated by the alternating potential applied between the dees 10 and 11 and by the direct cur-

rent magnetic field applied at right angles to the dees. The means for producing the magnetic field are not shown because they are well known to those skilled in the art. The charged particles travel in a spiralling path with ever increasing velocity until they emerge from the dees and impinge on the target 16. The target is activated by the bombardment and the characteristics of the bombarded material are studied.

It is to be understood, of course, that the dee chamber is maintained at a very low pressure. This is to prevent the charged particles from having too large a number of collisions with residual molecules.

Figure 2 illustrates in more detail the ion source 13. It comprises a tube 17 which carries at its end the filament 18. It is desired to maintain the filament 18 at a thermal emission temperature, and therefore, a suitable heating potential is maintained between the ends 19 and 20 of filament 18. The leads supplying the heating potential pass through the tube 17 and terminate in the filament ends 19 and 20, respectively. An upright supporting means 21 supports the cathode structure when it is removed from the dee chamber. A carriage 22 carries an upright plate 39 which is connected to the end 23 of the tube 17. The carriage 22 rides on a pair of rails 24 and is thus movable longitudinally of the cyclotron.

The cathode filament 18 and the tube 17 are received within the anode tube 26 during operation. The anode tube 26 has an internal diameter large enough to receive the tube 17. A head 27 extends upwardly from the end of tube 26 and is formed with a slot 28, for allowing the ions to emerge. The tubes 17 and 26 have a clearance between them large enough to allow gas to pass therebetween. The gas travels through the space between the outer wall of tube 17 and the inner wall of the tube 26 and passes the filament 18, where electron emission from the hot cathode flowing to the anode head 27 changes a certain portion of the gas molecules to ions. The tube 26 is maintained at a positive potential with respect to the filament 18. The charged particles emerge from the slot 28 into the dee chamber where they are accelerated.

When it is desired to remove the cathode, perhaps because the filament 18 has burned out, the tube 17 may be pulled longitudinally out of the tube 26 until the filament 18 is within the space formed by a plate 29 and a cylindrical member 31 attached to the plate 32.

The tube 17 has a plate 33 slidably mounted theron. The plate 33 holds a gasket, not shown, which forms an airtight seal between the plate and the tube. An opening 34 formed in plate 29 has a clamping member 35 which is detachably connectible to the plate 33. If the carriage 22 is moved longitudinally of the support member 36, the tube will slide past the plate 33 and the rubber gasket will prevent an air leak. When the filament is within the confines of the space formed by the plates 29 and 32 and cylindrical member 31, a door 37, which is pivotally supported by the pin 38, may be moved to a position which seals the end of tube 26. The door 37 may be controlled by air pressure in a manner well known to those skilled in the art. After the door 37 is closed, air is admitted to the chamber about the cathode 18 through a tube 15 in order to equalize the internal and external pressure. The clamping member 35 is then released by air pressure and the cathode may be withdrawn

completely. The plate 33 is removed with the cathode.

A driving means which may be an electric motor, for example, is designated generally as 43 and drives a belt 44 which passes over the pulleys 45, 46 and 47. The belt 44 travels between the tracks 24 and carries thereon a bracket 49. The bracket 49 may be moved longitudinally back and forth along the support 36 by the motor 43. The bracket 49 has a slot 51 formed therein for receiving a pivoted hook 52 carried on the carriage 22. The hook 52 is engageable with the bracket in the slot 51 and as the belt 44 is moved clockwise with respect to Figure 2, the cathode will be withdrawn from the tube 26, providing that the holding means 42 are released simultaneously. When the bracket 49 passes over the support 21, the catch of the support is released to allow it to pivot upwardly so that its roller 53 may engage the tube 17 of the cathode. The bracket 49 continues to move rearwardly, withdrawing the cathode from the anode tube. When the filament 18 is within the chamber formed between the plates 29 and 32, the door 37 is actuated and then the bracket 49 is moved further rearwardly to completely remove the cathode from the confines of the anode. Once the cathode is completely removed it may be lifted bodily upwardly and off the tracks 24 and replaced by a new one. If only the cathode is to be changed the motion of the belt 44 is reversed and the bracket 49 pushes the new cathode until the filament 18 has passed into the chamber between the plate 29 and 32. The clamp 35 engages plate 33 and forms an airtight seal. The pressure is reduced through the tube 15. During operation of the cyclotron the gas to be accelerated is admitted through tube 15. The door 37 is then opened and carriage 22 moved until the holding means 42 grasp the holding means 41 completing the operation.

The bracket 49 engages the carriage 22 to push it into the operating position. The hook 52 over-rides the bracket 49 until it engages the carriage 22. The support 21 remains upright supporting the tube 17 of the cathode until the carriage 22 releases a catch, shown in Figure 5, that allows the support 21 to pivot downwardly as the carriage 22 passes over.

Figure 5 illustrates the support 21 in detail. It comprises the lever 94 which is pivotally supported by the pins 96 on the bracket 97 connected to support member 36. A second lever 98 is pivotally connected to the bracket 97 by the pin 99 and its opposite end is pivotally connected to a short link 101 which has its opposite end pivotally fastened to the lever 94 intermediate its ends. A trigger portion 102 extends from the link 101 for releasing the brace formed by lever 98 and link 101. A stop 103 engages the pivot joint between lever 98 and link 101. A spring 104 connected about the pivot 96 urges the lever 94 to the up position shown in Figure 5.

The carriage 22 has a trigger engaging portion, not shown, which engages the trigger 102 to allow the lever 94 to be urged downwardly as the carriage passes over it. The belt 44, as best shown in Figure 1, comprises the two chains 106 and 107 attached to either side of the bracket 49.

Behind the bracket 49 connected between chains 106 and 107 are a plurality of transverse members 108. These members hold the support member 21 in its down position after the carriage 22 has passed thereover, thus preventing it from

coming up behind the carriage to jam the apparatus.

It is desirable at times to remove the anode. The anode tube 26 terminates in the plate 32, which is in turn mounted on a carriage 54 which rides on a pair of tracks 55 which are outside the tracks 24. The plate 29 and cylindrical member 31 are also mounted on the carriage 54 and move as a unit therewith. The plate 32 is clamped to a plate 56 by the clamping means 57. The plate 56 has formed therein an opening 58 large enough to allow the head 27 of the anode to be removed. A generally corrugated cylindrical member 59 connects the plate 58 with a plate 61 which is also formed with an opening for allowing the head 27 of the anode to be removed. The plate 61 is joined by the cylindrical member 62 to a plate 66 attached to the cyclotron chamber wall 12. A door 63 is pivotally supported by a pin 64 in the space between the plates 61 and 66. To remove the anode, the cathode must first be removed and taken off the track 24. After this has been done, the belt 44 is driven counter clockwise until the bracket 49 engages a hook 67 connected to the carriage 54. The belt is then driven clockwise by the driving means 43 thus pulling the carriage 54 along the tracks 55 until the anode head 27 is within the space between the plates 56 and 61. It is to be understood, of course, that the clamping means 57 must be released before the carriage 54 may be withdrawn. When the head 27 is within the confines of the member 59, the door 63 is swung to a closed position to maintain the vacuum within the dee chamber as the anode is removed. The tube 26 slides through a rubber gasket 61 mounted in a door 68, which is in turn connected to the plate 56. After the door 63 has been closed, the door 68 may be unclamped from the plate 56 and the anode removed completely. The means for clamping the door 68 to the plate 56 is shown in detail in Figure 6.

The door 68 is a circular plate which has an opening adjacent one edge for receiving the tube 26. The gasket 61 fits about the tube 26 to form an air tight seal.

A circular bracket 100 is mounted to the plate 56 by the pins 87 which are received in the slots 88 formed in the bracket 100. Thus the bracket 100 may be rotated slightly relative to the plate 56. Levers 89 are mounted on the pins 87 and links 91 are pivotally connected at either end to the bracket 100 and the ends of the levers 89. If the bracket 100 is rotated relative to the plate 56, the levers 89 engage and disengage, respectively the door 68. Thus, the door may be connected or disconnected to the plate 68. A rubber gasket 92 fits in a slot formed in the plate 56 to make an airtight seal. The bracket 100 is moved by a piston mounted in the cylinder 93. A rod 94 connects the piston to the bracket 100. The piston is actuated by air pressure which may be controlled in a well known manner from a remote position.

The support 21 provides vertical support for the tube 26 as it is removed in a manner similar to the support furnished the tube 11 of the cathode. The difference in the cathode diameter of tubes 11 and 26 does not materially effect the operation of the support.

When a new anode has been placed on the track 55, the belt 44 is driven in a counter-clockwise direction causing the bracket 49 to push the carriage 54 until the head 27 of the anode is within the chamber formed by the member 59.

The door 68 is a part of the anode assembly, and a new one is mounted on each anode. The door 68 is clamped to plate 56 and the pressure is reduced in the chamber between the doors 63 and 68 by exhaust line 70. When the pressure is sufficiently low, the door 63 is pivoted open and the anode slid into place through the gasket 67 until the clamping means 57 fastens the plate 32 to the plate 56. The cathode is then positioned in the manner previously described by returning the bracket 49 to a position adjacent the pulley 46 and placing a new cathode on track 24.

The cathode 18 operates at a high emission temperature, and it is desirable to liquid cool the cathode and anode tubes. It is also necessary to supply a heating potential to the cathode. A pair of tubes 110 and 111 are attached to a pair of female members 112 which extend through the plate 56. The plate 32 has a pair of male members 113 which extend therethrough and are engageable with the members 112 when the anode carriage 54 is clamped to the plate 56. A pair of tubes 114 extend from the members 113 to second female members 116 mounted through the plate 29. Second male members 117 are mounted on plate 39 and are engageable with the members 116.

As shown in Figure 7, a pair of tubes 118 and 119 extend from the members 117 into the cathode tube 17. These tubes supply the heating potential to the filament 18 and also carry circulating fluid for liquid cooling the cathode. The connection members 112, 113, 116 and 117 are insulated from the plates 56, 32, 29 and 39 and form fluid tight seals when connected.

Figures 3 and 4 illustrate apparatus for automatically removing the anode and cathode from the tracks 24 and 55 when they have been withdrawn from the dee chamber. The apparatus 40 comprises a carriage which has a base plate 69 mounted on wheels 71 which ride on tracks 72. As shown in Figure 1, the tracks 72 are placed transversely of the frame 36. Driving means, as, for example, an electric motor 73 is mounted 45 on the under side of the base 69 and is connected to the wheels 71 to provide motive power for moving the carriage forwardly and rearwardly. A generally U-shaped upright member 74 is mounted on the base 69. A shaft 76 is rotatably supported in the legs of the support 74 adjacent the upper end. A second driving means 77 is mounted on the base plate 69 and carries a gear 78. The shaft 76 has a gear 79 rigidly mounted thereto and a chain drive 81 connects the gears 78 and 79. Rigidly connected to the shaft 76 are two pairs of arms 82 and 83. The arms extend outwardly from the shaft 76 and terminate in hooks 84 and 86, respectively. The arms 82 and 83 extend from the shaft 76 adjacent both ends of the U-shaped support 74. The arms may be rotated relative to the carriage by the driving means 77. The hooks at the end of the arms are adapted for engaging the cathode and anode structures to remove them from the tracks 55 and 56. The arms may also be used for placing a new anode or cathode on the track 24. To remove the cathode structure, a pair of arms must be empty and the carriage is moved on the track 72 until the hook 86 is beneath the cathode. Driving means 77 is then actuated until the cathode is picked up. The carriage is then backed from the member 36 and the driving means 77 is actuated to move the other pair of arms into position with its new cathode. The 60 carriage is then once again moved toward the

70 cathode. Driving means 77 is then actuated until the cathode is picked up. The carriage is then backed from the member 36 and the driving means 77 is actuated to move the other pair of arms into position with its new cathode. The carriage is then once again moved toward the

member 36 until the new cathode is directly above the track 24 and is lowered thereon by the driving means 77. The arc distance between supporting hooks on adjacent arms must be great enough so that when the arms are replacing a cathode, the removed structure does not engage the support 36 on the driving means 43. This is accomplished by making the angle between arms 82 and 83 sufficiently great. It is sometimes desirable to use more than two pairs of arms so that the anode and cathode may both be changed. This requires four pairs of arms, one pair to carry the new anode, one pair to carry the new cathode, one empty pair to remove the old cathode, and one pair to remove the old anode. Arms may be added to the shaft 76 as desired.

All the motors, doors, and release mechanisms may be actuated remotely by the operator 87 illustrated in Figure 1. The structure for actuating these members is not shown in detail because they are well known to those skilled in the art. For example, the two motors 73 and 77 carried on the carriage are conventional electric motors, and a suitable electrical connection between these motors and the operator makes it possible for him to control their motion. The same thing is true of the motor 43. Likewise, the release mechanisms 42 and 57 may be actuated by compressed air in a well known manner. The operator 87 can operate the valves from his remote position.

It is seen that this invention provides means for removing the anode and cathode of a cyclotron without the necessity of exposing a human being to the residual radiations from the cyclotron. It is to be understood, of course, that the operating mechanism of the cyclotron is turned off during the ion source change, but a lot of residual radiation remains after the magnetic field has been removed and the alternating potential disconnected from the dees.

Although this invention has been described with respect to particular embodiments thereof, it is not to be so limited as changes and modifications may be made therein which are within the full intended scope, as defined by the appended claims.

We claim:

1. Means for automatically changing the cathode of a cyclotron having an ion source with a first tube received within a second tube and the cathode filament connected to the end of said first tube comprising, means for moving said first tube longitudinally of said second tube, a movable door for closing the end of said second tube after the said first tube has been withdrawn therefrom, and an air lock formed about the outer end of said first tube.

2. Means for removing the cathode of a cyclotron comprising, driving means connectable with said cathode to move it longitudinally of said cyclotron chamber, an air lock connected to said cyclotron, a door within said air lock movable to seal the opening which normally receives said cathode, and said driving means removing said cathode from said air lock.

3. In a cyclotron having a tubular anode with an upwardly extending portion adjacent the inner end thereof and a tubular cathode received within said anode, means for removing said cathode comprising, a longitudinal track extending outwardly from one end of said cyclotron, a carriage received on said track and connected to the outer end of said cathode, an air lock about

the outer end of said cathode, driving means for moving said carriage along said track, and a door movable across the open end of said anode after said cathode has been removed therefrom, prior to removing said cathode from said air lock.

4. Apparatus for automatically removing the anode of a cyclotron comprising, a carriage mounted on a longitudinal track extending out from said cyclotron, the anode of said cyclotron connected to said carriage and extending through an air lock to within the confines of said cyclotron, flexible means connected to said carriage for moving it longitudinally of said track, and a door within said air lock movable to an air seal position when the inner end of said anode is within the confines of said air lock.

5. A system according to claim 3 wherein the anode of said cyclotron is connected to a second carriage which is mounted on a second pair of tracks and which is movable by said driving means longitudinally of said track, a second air lock with a second door movable to an air-seal position when the inner end of said anode is within the confines of said second air lock, and said anode movable from said second air lock.

6. Means for automatically removing and replacing the cathode of a cyclotron comprising, a longitudinal cathode connected to a carriage, a longitudinal track extending outwardly from said cyclotron and supporting said carriage, an air lock adjacent the outer end of said cathode, driving means for moving said carriage longitudinally of said track, a second track transverse of said first track, a second carriage mounted on said second track, a plurality of arms extending out from said second carriage, second driving means connected to said second carriage, a first pair of arms on said second carriage engageable with the removed cathode to lift it from said first track, a second pair of arms carried on said second carriage with a new cathode thereon movable to place said new cathode on said first track, and said first driving means engageable with said new cathode to move it through the air lock and into the cyclotron chamber.

7. A system according to claim 6 wherein said first driving means is engageable with a third carriage connected to the anode of said cyclotron to move it through a second air lock out of the confines of said cyclotron.

8. In a system according to claim 7 wherein said second carriage has a third pair of arms for removing said old anode and a fourth pair of arms for placing a new anode on said third pair of tracks.

9. In a mechanism for automatically removing and changing the cathode of a cyclotron, replacement means comprising, a portable carriage, driving means for moving said carriage, an upright support means on said carriage, a horizontal shaft rotatably supported in said upright means, second driving means connected to said shaft, and a plurality of arms rigidly attached to said arms and extending therefrom.

10. In apparatus for changing the cathode and anode of a cyclotron, replacement means comprising, a portable carriage, first driving means connected to said carriage, an upright support mounted on said carriage, a horizontal shaft rotatably supported in said upright member, second driving means connected to said shaft, a plurality of arms extending from said shaft, and engaging means adjacent the end of each arm for engaging the cathode and anode of the cyclotron.

11. Apparatus for changing the cathode of a

cyclotron comprising, a cathode extending longitudinally into the dee chamber of said cyclotron, an air lock about the outer end of said cathode, a longitudinal track extending from said cyclotron, a carriage received on said track, driving means connected to said carriage, a support member pivotally mounted between said tracks and movable to a first position to support the free end of said cathode, and movable to a second position below the level of said tracks so that the carriage may pass there-over.

12. Apparatus for changing the cathode and anode of a cyclotron comprising, a longitudinal cathode received within the hollow confines of a longitudinal anode, a first carriage connected to the outer end of said cathode, a second carriage connected to the outer end of said anode, a first air lock mounted on said second carriage and said cathode movable through said first air lock into said anode, a first door within said first air lock movable to seal the end of said anode when said cathode is removed, a second air lock connected to said cyclotron, a second door pivotally supported within said second air lock and movable to close said second air lock when the anode has been substantially removed from the cyclotron, driving means engageable with said first and second carriage to move them longitudinally in and out of said cyclotron, and means for closing said first and second doors.

13. In a system according to claim 12, means for removing said cathode and anode comprising, a third movable carriage, second driving means connected to said third carriage for moving it transversely of said cyclotron, a generally upright support mounted on said carriage, a transverse shaft rotatably mounted adjacent the end of said third carriage, third driving means connected to said shaft, a plurality of arms extending from said shaft, and engaging portions at the outer ends of said arms engageable with the cathode and anode.

10

14. Apparatus for changing the cathode of a cyclotron comprising, a generally tubular cathode extending into the dee chamber of said cyclotron, a movable carriage connected to the outer end of said cathode, driving means connected to said carriage to move it longitudinally of said cyclotron, a hollow anode extending into the dee chamber of the cyclotron with the cathode received therein, a second carriage mounted to the outer end of the anode, a first air lock mounted on the second carriage, a second air lock mounted on said cyclotron, first fastening means connecting said first carriage to said second carriage, second fastening means connecting said second carriage to said cyclotron, driving means engageable with said first and second carriages to move them longitudinally of said cyclotron, and means for actuating said first and second air locks.

15. In a system according to claim 14, a support member pivotally supported on an extending portion of said cyclotron, said support member movable to a first upright position with an engageable portion in contact with the anode or cathode, and movable to a second horizontal position for allowing the first and second carriages to pass there-over.

16. In a system according to claim 14, removing means comprising, a movable base member, generally upright supporting means, second driving means connected to said removing means, a shaft rotatably supported in said upright supporting plurality of arms extending from said shaft, third driving means connected to said shaft, and cathode and anode engaging portions adjacent the ends of said arms to remove and replace cathodes and anodes.
